UNITED STATES PATENT OFFICE.

WILLIAM A. TROUT, OF LOS ANGELES, CALIFORNIA, ASSIGNOR, BY MESNE ASSIGNMENTS, TO EMSCO DERRICK & EQUIPMENT COMPANY, OF LOS ANGELES, CALIFORNIA, A CORPORATION OF CALIFORNIA.

STEEL DERRICK.

Application filed May 14, 1924. Serial No. 713,323.

My invention relates to derricks and is particularly applicable to steel derricks used in the drilling of oil wells and the like. In the drilling of the well, it is subjected to a very heavy duty, in that it is used to support the casing in the well, which is very heavy, and in that it is called upon to take the heavy strains incident to pulling this casing in case it becomes "frozen." After the well is drilled, however, and the casing is set in place, the derrick is never called upon to lift such excessive loads, being ordinarily used merely for pumping and for handling the tubing and rods. If the derrick is made sufficiently heavy to perform the heavy duty during the drilling period, it will prove much heavier than is necessary for operation during the pumping period.

Some companies have, therefore, adopted the plan of making a heavy derrick which is utilized during the drilling period, this derrick being dismantled and replaced by a light derrick which is used during the pumping period. It is an object of my invention to provide a derrick which may be used during the drilling period and which is sufficiently strong to withstand any strains which may be put thereon during that period, this derrick being so constructed that a portion thereof can be removed after the drilling period, thereby greatly lightening the derrick and cutting down the investment therein. This I accomplish by providing, in addition to the main legs of the derrick, certain auxiliary legs which are secured in place during the drilling period and which are removed at the conclusion of the drilling period, leaving the lighter construction for subsequent pumping.

I have found that it is difficult where a double leg is used, that is to say, a leg consisting of a permanent main member and an auxiliary removable member, to make these legs each take their proper proportion of the load, particularly in a steel derrick which is relatively inelastic. It is, therefore, an object of my invention to make the auxiliary legs adjustable in length so that when installed in the derrick, they can be adjusted to take any desired portion of the double load. This arrangement also permits of a ready removal of the auxiliary legs at the conclusion of the drilling period, and allows

the auxiliary legs to be used in derricks which may have slightly different dimensions.

Further objects and advantages will be made evident hereinafter.

Referring to the drawing, which is for illustrative purposes only—

Fig. 1 is an elevation through a corner of the derrick showing the auxiliary leg in place, the derrick being broken away to show only the upper and lower portions of the legs.

Fig. 2 is a section on a plane represented by the line 2—2 of Fig. 1.

Fig. 3 is a section on a plane represented by the line 3—3 of Fig. 1.

Fig. 4 is a diagrammatic plan view on a much smaller scale showing the location of the main and auxiliary legs.

In the form of the invention illustrated, four main legs 11 are provided, these legs consisting principally of angle iron and extending from a foundation 12 up to a top structure 13, this top structure including the so-called water table 14 of the derrick. The legs 11 are connected by cross members 15, 16 and 17, and by suitable cross bracing, not shown, the general form of bracing used in an oil well derrick being preferably followed. The angle iron legs 11 are made amply strong to take care of any strain which may be imposed thereon during the pumping period of the well, but they are not sufficiently strong to sustain the enormous loads necessary to placing or pulling casing or other operations during the drilling period of the well.

For the purpose of reinforcing the legs 11 so that the derrick may be used for drilling, I provide auxiliary legs 20. These legs preferably consist of a heavy pipe section which fits at its upper end into a cap or socket 21, which may be secured to the member 16 or to some other member in the upper portion of the derrick. The lower end of the pipe 20 has a nut 22 fixed therein, preferably by being welded. Threaded in the nut 22 is a screw 23. The screw 23 fits into a socket or lower thrust bearing 24, which is preferably secured by means of bolts 25 inside the derrick leg 11 near the bottom thereof. A lock nut 26 is also threaded on the screw 23, the lock nut 26 and the screw 23

being provided with holes 27, into which a round bar may be inserted for the purpose of turning them. A loose pipe member 28, sliding over the pipe 20 and the nut 22, is 5 provided for covering the screw 23. This pipe may be lifted upwardly, sliding freely over the pipe 20 to give access to the holes 27. The pipe leg 20 is secured to the angle 10 11 at intervals by clamps 30, these clamps being for the purpose of tying the two legs together, so that one reinforces the other against buckling, the clamps 30 being so arranged, however, that a limited vertical 15 movement between the two legs is possible. I provide four of the pipe legs 20, placed as shown in Fig. 4, inside the angle legs 11. The parts being erected as shown, it is possible to put any desired strain on each of the pipe legs 20 by loosening the nut 26 and 20 turning the screw 23, the amount of strain on each of the screws being readily judged by the resistance offered to turning of the screw. After each of the legs 20 is suitably 25 adjusted, the screws 23 are locked by means of the nuts 26.

By the use of my invention, it is possible to set up each of the auxiliary legs 20 so that they take a fairly definite proportion of the load during the drilling period. Whenever 30 the drilling period is over, it is possible to remove the auxiliary legs 20, thus leaving the light derrick for the subsequent pumping operations.

I claim as my invention:

1. In a derrick, the combination of: a top structure; four main legs partially supporting said top structure; four auxiliary legs also partially supporting said top structure; and means for regulating the 40 load assumed by said auxiliary legs.

2. In a derrick, the combination of: a top structure; four main legs partially supporting said top structure; four auxiliary legs also partially supporting said top structure; and means in each of said auxiliary legs for regulating the load imposed on said leg. 45

3. In a derrick, the combination of: a main structure; auxiliary legs set in said 50 main structure; and means for regulating the load imposed on each of said legs.

4. In a derrick, an auxiliary leg structure comprising: an upper thrust member secured to the upper portion of the derrick; 55 a lower thrust member secured to the lower portion of the derrick; a leg abutting at one end on one of said thrust members; and an adjustable member between the other end of said leg and the other thrust member.

5. In a derrick, an auxiliary leg structure 60 comprising: an upper thrust member secured to the upper portion of the derrick; a lower

thrust member secured to the lower portion of the derrick; a leg abutting at one end on one of said thrust members; and an adjusting screw through which the thrust of the other end of said leg is transmitted to the other of said thrust members. 65

6. In a derrick, the combination of: a top structure; four main legs partially supporting said top structure; four auxiliary legs also partially supporting said top structure; means for attaching each of said auxiliary legs at a plurality of points to one of said main legs; and means for regulating 75 the load assumed by said auxiliary legs. 70

7. In a derrick, the combination of: a top structure; four main legs partially supporting said top structure; four auxiliary legs also partially supporting said top structure; means for attaching each of said auxiliary legs at a plurality of points to one of said main legs; and means in each 80 of said auxiliary legs for regulating the load imposed on said leg. 85

8. In a steel derrick, the combination of: a top structure; an angle iron leg partially supporting said top structure; a pipe leg also partially supporting said top structure; and means for regulating the proportion 90 of the total load taken by each of said legs. 90

9. In a steel derrick, the combination of: a top structure; an angle iron leg partially supporting said top structure; a pipe leg also partially supporting said top structure; means for attaching said pipe leg to said angle iron leg at intervals in such a manner as not to interfere with a longitudinal movement thereof; and means for regulating the proportion of the total load taken by each of said legs. 95 100

10. A derrick, including an inner leg and an outer leg; and means near the lower ends of said outer and inner legs for shifting the load from one leg to the other above said means. 105

11. The combination with a sectional reinforcing leg for derricks of an expandible device adapted to engage ends of adjacent leg sections, and means to expand and contract the device to adjust the length of the leg. 110

12. The combination with a sectional reinforcing leg for derricks of an expandible device adapted to engage ends of adjacent leg sections, means to expand and contract the device to adjust the length of the leg, and means to lock the device in adjusted 115 position. 120

In testimony whereof, I have hereunto set my hand at Los Angeles, California, this 28th day of April, 1924.

WM. A. TROUT.
